UNITED STATES PATENT OFFICE.

EDWIN J. SCARSETH, OF GALESVILLE, WISCONSIN.

GAME APPARATUS.

Application filed January 14, 1926. Serial No. 81,268.

This invention relates to improvements in game apparatus and more particularly that class embodying a target, a projectile, and means for impelling the projectile in the direction of the target, and one of the objects of the present invention is to provide an apparatus of this class which will require the exercise of skill and judgment on the part of the player.

The apparatus embodying the invention includes a plurality of target members, means for positioning a projectile, and means for impelling the projectile, and another object of the invention is to so construct the impelling means that it may be adjusted, at the discretion of the player, to impel the projectile in various directions so that, if the player is skillful, he may cause the projectile to strike a selected one of the target members.

Another object of the invention is to provide, in apparatus of this class, two impelling members so formed that one of the members will, when actuated, impel the projectile in an upward and forward direction in an elevated path of flight and the other impelling means, when actuated, will impel the projectile forwardly in a less elevated path of flight, the invention further contemplating so forming the striking portions of the impelling members that the projectile may be impelled directly forwardly or to either side, depending upon the adjustment of the said members.

35 Another object of the invention is to provide, in game apparatus of the class referred to, target members so constructed and so mounted that when one or another of several radial target blades of any one of the
40 members is struck by the projectile, rotary movement will be imparted to the respective target member about a support upon which it is mounted and the target member will come to rest in one or another of several positions which it is capable of assuming, in equilibrium.
45

Another object of the invention is to provide means for automatically registering the number of times the impelling members are actuated, so that the number of plays made by each player may be accurately determined.

Another object of the invention is to so construct the apparatus that after the projectile has been impelled it will be automatically returned to position to be again

impelled through actuation of one or the other of the impelling members.

In the accompanying drawings:

Figure 1 is a side elevation of the game apparatus embodying the invention.

Figure 2 is a vertical front to rear sectional view through the apparatus.

Figure 3 is a horizontal sectional view on the line 3—3 of Figure 2, looking in the direction indicated by the arrows, and illustrating a portion of the apparatus in top plan. 65

Figure 4 is a vertical transverse sectional view through the target members.

Figure 5 is a perspective view of one member of the indicating mechanism.

Figure 6 is a sectional perspective view of one of the impelling members.

Figure 7 is a similar view of the other impelling member. 75

The game apparatus embodying the invention includes a base 1 which may be of wood or metal or any other material found suitable for the purpose and which has its upper surface 2 inclined from end to end, the base being of oblong rectangular form, as shown in Figure 3. In order to prevent the projectile, which is indicated by the numeral 3, and of spherical shape, being impelled through space beyond the boundaries of the apparatus, a guard, indicated in general by the numeral 4, is provided, and this guard is preferably of wire mesh material and comprises sides 5, a back 6, and a rearwardly and downwardly curved top 7, the sides 5 preferably having their upper edges inclined downwardly from the opposite ends of the forward edge of the said top 7. This guard likewise serves to enclose the target 80

unit and this unit comprises upstanding side plates 8 which are preferably secured at their lower ends to the opposite side edges of the base 1 near the rear thereof, and these side plates supporting a rod 9 upon which the target members are mounted. The target members are indicated in

general by the numeral 10, and each of said members comprises a cylindrical body 11 which may be of wood or any other material found suitable for the purpose and which is formed with a rectangular opening indicated by the numeral 12 extending therethrough from side to side. The opening 12 is located eccentrically of the body 11 with one of its corners, indicated by the numeral 13, located approximately at the axis of the

said body. A target blade 14 is stepped into or otherwise fixed to the body 11 so as to project from the periphery thereof substantially opposite the corner of the opening 12 opposite the corner 13, the blade extending in a radial direction and other blades 15 are likewise fixed to the body and project from the periphery thereof and are spaced from the blade 14 90 degrees. 5

It will be observed that there is no blade at that side of the body next adjacent to which the corner 13 of the opening 12 is located, and by arranging the opening eccentric to the axis of the body, the body is substantially equally balanced in its 10 rotative movement about the rod 9, it being evident that when the target member is stable or at rest, one or another of the corners of the opening 12 will accommodate the rod 9 and, therefore, when the said target member comes to rest it will remain stationary until subsequently rotated through impact of the projectile against one or another of the blades 14 and 15. As shown in Figures 15

3 and 4 of the drawings, the representation of a face, indicated by the numeral 16, is preferably painted or otherwise represented upon one side of each of the blades 14 and 15, namely that side which will be presented 20 in a forward direction when such blade is in a perpendicular position. As illustrated in Figures 2, 3 and 4 of the drawings, the target members 10 are initially so positioned upon the rod 9 that the blade 14 of each 25 of the members will project forwardly and the blades 15 will project one in an upward direction and the other downwardly, and the members are so supported that when they occupy this position or any other position, it will be possible for the projectile 3 to be impelled below the lower end of any downwardly projecting blade, above the upper end of any upwardly projecting blade, and behind the end of any rearwardly projecting blade. The target members are, of course, all independently rotatable about the rod 9. The numeral 17 indicates side plates which are secured at their lower edges to the opposite longitudinal edges of the base 1, at the front thereof, and which occupy substantially the same planes as the respective sides 5 of the guard 4. As will presently be explained, these side plates constitute a support for the impelling members 50 and the registering mechanism, and in order that the projectile 3 may be properly positioned for impact of the impelling members therewith, a positioning member 18 is mounted upon the inclined upper surface of the base 1, at the forward end thereof, and preferably consists of a length of wire which is bent midway between its ends to provide an arcuate bight 19 and spaced diverging arms 20 which extend rearwardly from the bight and are anchored at their rear ends 55 in openings 21 formed in the upper side of the base 1, the said ends of the arms being anchored to the base near the lateral edges thereof and relatively close to the rear ends of the side plates 17. It will now be evident that when the projectile rolls down the inclined surface of the base it will engage one or the other of the arms 20 of the positioning member and will finally come to rest in the bight 19, thus assuming a position immediately at the front of the base and midway between the lateral edges thereof. 60

As heretofore stated, two impelling members are employed and these members are indicated in general, one by the numeral 22 and the other by the numeral 23. Each of these members is preferably formed from a single integral sheet metal blank and comprises a front portion 24 and spaced rearwardly projecting side portions 25 formed at the opposite sides of the front portion by bending the blank along parallel lines. The upper portion of the blank is bent to extend rearwardly to provide a top portion 26 extending rearwardly above the upper edges of the side portions 25 and having its rear end portion projecting beyond the free edges of the said side portions 25 and suitably formed to provide a finger piece indicated by the numeral 27. A rod 28 is slidably, adjustably fitted through openings 29 formed in the side plates 17 and is provided at one end with a finger knob 30 which may be grasped for the purpose of longitudinally adjusting said rod. The rod 28 passes through openings 31 formed in the side members 25 of the two impelling members 22 and 23 and in this manner the members are suspended upon the rod for independent swinging movement, the openings 31 being located near the rear upper corners of the side members 25 so that the members 22 and 23 normally assume a forwardly and downwardly inclined position substantially as shown in Figures 1 and 2 of the drawings, the finger pieces 27 extending upwardly and forwardly as likewise shown in the said figures. The members 22 and 23 are, as stated, independently supported for swinging movement and they are preferably spaced with respect to each other by a washer 32 disposed upon the rod 28, and are held against displacement longitudinally along the rod by collars 33 formed or fixed upon the said rod. By reference to Figure 3 of the drawings, it will be evident that by adjusting the rod 28 transversely of the front of the apparatus, either of the members 22 and 23 may be brought into position substantially opposite the projectile 3 which is resting in the bight 19 of the positioning member 18, and it will furthermore be evident that either of the said impelling members may be brought not only to a position 100

110

120

130

directly in front of and opposite the projectile, but to other positions somewhat laterally displaced with respect to the projectile. This permits of a direct impact of the 5 lower end of the front 24 of either member directly against the forward side of the projectile or, if the member is somewhat laterally displaced, it, when actuated, will strike the projectile near one side or the other so 10 as to impel the projectile rearwardly toward the right or toward the left rather than directly rearwardly, and in order that this result may be more perfectly attained, the lower portion of the front 24 of the impelling 15 member 22 is transversely curved as indicated by the numeral 34, the said front being otherwise substantially straight in a vertical direction. In a similar manner, the lower end portion of the front 24 of the impelling member 23 is transversely curved, as indicated by the numeral 35, and its said portion is likewise dished along a vertical line, as indicated by the numeral 36, so that its lower extremity will be curved to a greater or less extent in a forward direction or, 20 in other words, in the direction in which it is swung to impel the projectile.

When the target members have been properly arranged as before described, the player determines which one of the impelling members he will use and adjusts the supporting rod 28 to bring the said member into position opposite the projectile 3 or slightly to one side or the other thereof and then 25 suddenly presses down upon the finger piece 27 of the impelling member, causing the member to swing quickly rearwardly or in the direction of the projectile and, by impulsive force, drive the projectile in the direction of the target. The player will, of course, select which one of the target members he wishes to rotate and will endeavor to strike one or another of the blades of the said member. If it is desired to strike a 30 downwardly projecting blade of any one of the target members, the player will naturally select the impelling member 22, inasmuch as the lower portion of the front of this member is substantially straight on a vertical line and while the projectile 3 will be impelled in an upward direction, it will not be impelled to such a height as it would be if the member 23 had been brought into use. Therefore, the player may select one 35 or the other of the impelling members, depending upon whether he wishes to impel the ball at a low elevation or a higher elevation. By laterally adjusting the selected impelling member, where one of the target members at or near the end of the series is the objective one, the projectile may be directed toward the right or toward the left as well as upwardly.

The purpose which each player will have 40 in view, in competition with other players,

will be to impel the projectile with a minimum number of plays, through the medium of the impelling members, in a manner to effect change in position of the target members so that all of the same target members 70 will finally occupy a position with the blade 14 extending downwardly and the blades 15 extending one in a forward direction and the other in a rearward direction, or, in other words, precisely the reverse of the position 75 shown, for example, in Figure 2 of the drawings, and in such position of each target member the blank space of the blade 14 will be presented to the player's view and none 80 of the face representations 16 will be visible. It will be evident at this point that a player, in order to accomplish his purpose, must exercise judgment in determining the target member at which the projectile is to be directed and whether it will be advisable to 85 employ the impelling member which will impel the projectile in an upward direction to strike an upstanding target blade or in a nearly horizontal direction in order to strike a downwardly projecting blade. 90

In order that the number of plays made by each player may be automatically registered, registering means is employed, actuated through the impelling movement of the members 22 and 23 and this mechanism comprises a wheel 37 rotatably mounted upon a stub shaft 38 upon one of the side plates 17, the wheel being provided with peripheral teeth indicated by the numeral 39. Upon the outer face of the wheel 37, opposite each tooth, there is printed an indicating number, which numbers are indicated by the reference numeral 40, and these numbers are arranged in numerical order throughout the entire series. An indicating arrow or pointer 41 is depicted upon the outer side of the said side plate 17 and positioned for registration of the teeth 39 therewith, in the rotation of the registering wheel 37. The wheel 37 is intended to be rotated the distance of 100 one tooth at the time of operation of either of the impelling members 22 and 23 and the means for effecting this actuation of the wheel comprises a rod 42 pivotally engaged at one end through an opening 43 formed in 105 that one of the side members 17 opposite the one beside which the wheel 37 is positioned. The rod 42 is provided at its said end with a head 43 which prevents longitudinal displacement of said rod in one direction. The 110 rod extends through an inclined slot 44 formed in the other side plate 17 and is bent at right angles to provide an upwardly and rearwardly extending arm 45 positioned close to the outer side of the said plate. The 115 said arm 45 is bent at right angles to provide a ball portion 46 which rests in engagement with the teeth of the wheel 37, and beyond this portion is bent downwardly as 120 at 47 beside the outer face of the wheel and 125 beyond this portion is bent downwardly as 130

thence rearwardly, as at 48, the said portions 47 and 48 serving to normally maintain the member 42 in overbalanced position with its ball portion 46 in engagement with the teeth of the wheel 37. It will now be evident that when the member 42 assumes a normal position, it will rest at its portion adjacent the bend at the lower end of the arm 45, in the lower end of the slot 44, its portion 46 engaging against the abrupt face of one of the teeth 39 of the registering wheel 37. With the member in this position, the projectile 3 will rest against the portion of the member which extends across the front of the apparatus, the said portion of the said member being located at such distance above the upper surface of the base 1 that the upper and forward side of the projectile 3 will contact the intermediate portion of the said member 42. It will now be evident that when either of the impelling members 22 and 23 is actuated, the member will first strike the projectile to impel the same and immediately subsequently will strike the member 42 to swing the same about its pivot end 43, in an upward and rearward direction, to cause the ball portion 46 of the said member to impart rotary motion to the registering wheel 37 a distance of one tooth and, when the projectile 3 returns to position resting in the bight of the positioning member 18, it will strike the portion 42 and restore the same to normal position, the ball portion 46 of the member riding over the next tooth of the series and engaging behind the same.

In order that the lower ends of the impelling members may strike the projectile 3 in the most effective manner, the base 1 at its rear edge and upper side is beveled as indicated by the numeral 49, thus affording ample clearance for the said ends of the impelling members.

In order that the projectile 3 may be held assembled with the remainder of the apparatus when the apparatus is not in actual use, a retaining member 50 is provided and comprises a base portion 51 which is secured to the upper side of the base 1 between one of the side plates 17 and the adjacent one of the side members 20 of the positioning member 18, and upstanding cupped resilient side members 52 between which the projectile may be frictionally fitted and retained.

Having thus described the invention, what I claim is:

1. In game apparatus of the class described, a plurality of independently movable target members, projectile positioning means located opposite the same, impelling members operatively supported with relation to the said positioning means, one of said impelling members having an impact surface substantially straight on a plane at right angles to the axis of movement of the

member, the other member having an impact surface inwardly curved with respect to such plane whereby to impel a projectile sustained by the positioning means in an upward direction, and means supporting said impelling members and adjustable to selectively bring said members into operative relation to the positioning means.

2. In game apparatus of the class described, a plurality of independently movable target members, projectile positioning means located opposite the same, an impelling member operatively arranged with relation to the said positioning means to deliver impactive force against a projectile sustained by the said positioning means, and indicator mechanism including an element simultaneously actuated through actuation of the impelling member.

3. In game apparatus of the class described, a plurality of independently movable target members, projectile positioning means located opposite the same, an impelling member operatively arranged with relation to the said positioning means to deliver impactive force against a projectile sustained by the said positioning means, and indicator mechanism including an element actuated through actuation of the impelling member, the said indicator mechanism comprising a number wheel having a peripheral series of teeth, and a pawl element co-acting with the teeth and movable through actuation of the first mentioned element of the said indicator mechanism.

4. In game apparatus of the class described, a target member, projectile positioning means located opposite the same, an impelling member operatively arranged with relation to the said positioning means, a registering number wheel mounted for rotation and having a peripheral series of teeth, a rod supported at one end for pivotal movement and extending transversely across the path of movement of the impelling means, and a pawl actuated through movement of the rod through impact of the impelling means therewith to effect rotation of the said number wheel.

5. In game apparatus of the class described, projectile positioning means, an impelling member operatively arranged with relation thereto to deliver impactive force to a projectile sustained by the positioning means, and a target unit positioned in advance of the said positioning means and comprising a symmetrical body having an eccentrically located opening therein, a suspension element extending through the opening, target elements projecting from the periphery of the body at diametrically opposite points thereof, a third target element projecting from the periphery of the body and spaced from the first mentioned elements approximately ninety degrees, the

eccentric disposition of the said opening being in the direction of the last mentioned target element.

6. In game apparatus of the class described, projectile positioning means, an impelling member operatively arranged with relation thereto to deliver impactive force to a projectile sustained by the positioning means, and a target unit positioned in advance of the said positioning means and comprising a cylindrical body having a rectangular opening extending therethrough from side to side and positioned eccentrically with one corner located substantially at the axis of the body, a target element projecting from the periphery of the body substantially opposite the opposite corner of the opening, and other target elements projecting from the periphery of the body and

spaced from the first mentioned target approximately ninety degrees, and a suspension element extending through the opening.

7. In game apparatus of the class described, a plurality of independently movable target members, projectile positioning means located opposite the same, a longitudinally shiftable rod located in juxtaposition to the projectile positioning means and extending transversely with respect thereto, and impelling members suspended from said rod and capable of independent swinging movement thereon, adjustment of the said rod serving to position the said impelling members selectively to deliver impactive force against a projectile sustained by the positioning means.

In testimony whereof I affix my signature.
EDWIN J. SCARSETH. [L.S.]
